UNITED STATES PATENT OFFICE.

FREDERICK A. HART, OF NEWARK, NEW JERSEY, ASSIGNOR TO UNDERWOOD COMPUTING MACHINE COMPANY, OF NEW YORK, N. Y., A CORPORATION OF NEW YORK.

COMBINED TYPE-WRITING AND COMPUTING MACHINE.

1,315,303.

Specification of Letters Patent.

Patented Sept. 9, 1919.

Application filed October 9, 1917. Serial No. 195,526.

To all whom it may concern:

Be it known that I, FREDERICK A. HART, a citizen of the United States, residing in Newark, in the county of Essex and State 5 of New Jersey, have invented certain new and useful Improvements in Combined Type-Writing and Computing Machines, of which the following is a specification.

This invention relates to an improvement 10 in combined typewriting and computing machines of the Underwood addendograph type, and is illustrated in connection with the mechanisms disclosed in the applications of Frederick A. Hart, Serial No. 70,898, filed 15 January 8, 1916 (now Patent No. 1,285,150, dated November 19, 1918,), Henry L. Pitman, Serial Nos. 24,390, 144,825 and 176,303, filed April 28, 1915, January 27, 1917, and June 22, 1917, respectively, and Arthur A. 20 Johnson, Serial No. 112,645, filed August 2, 1916.

In this form of machine, the numeral keys supply the power not only for operating the type-actions, but also for operating 25 the computing mechanism, and there are various safeguards, in the form of locks and shifting devices. The burden of these safeguards on the numeral keys renders their action slow and heavy. It is, hence, desirable to relieve the numeral keys of this extra work when not actually computing. Provision is made, therefore, for disconnecting 30 portions of the computing mechanism from the numeral keys when not actually in a computing zone. Further provision is made 35 for throwing all of the computing mechanism out of action when it is desired to merely typewrite, and not compute. This improvement includes a control of the locking means for the numeral keys, which prevents more than one numeral key from being operated at a time, and which insures 40 that each numeral key completes its up-and-down stroke before the operation of another 45 numeral key. This locking mechanism for the numeral keys is controlled from the type-writer carriage by a stop corresponding to the computing zone, so that this locking mechanism will be out of operation when 50 not in a computing zone, and will be brought into operation when in the computing zone. This enables a more rapid operation of the numeral keys, as, in ordinary typewriting without interlocks, the actions of the 55 numeral keys when rapidly operated overlap

each other. When computing, the overlapping of the action of the numeral keys is not desired, on account of the possibility of error; hence, the need of throwing in the numeral-key-interlocks when in a computing 60 zone.

The numeral keys in this form of machine are also called upon to shift the driving gear or rack, driven by the numeral keys and connected to drive the master wheel, 65 into and out of driving mesh with the train which it drives. This is done at each stroke of a numeral key, and is controlled, in the present invention, so as to remain out of action until a computing zone is reached. 70

The numeral keys may be entirely disconnected from the computing mechanism by a manually-operated arrangement, which is also connected to throw out the control from the carriage of the numeral-key-interlocks and the driving rack-shifting mechanism, so that these will not be operated in or out of a computing zone when the computing mechanism is silenced. 75

Other features and advantages will here- 80 inafter appear.

In the accompanying drawings,

Figure 1 is a vertical section, from front to rear, with parts omitted to simplify the showing, and illustrating the actuator as 85 disconnected from the valuating or indexing bail.

Fig. 2 is an enlarged detail view of the full-stroke locking mechanism, illustrating the same in its silenced position. 90

Fig. 3 is a skeleton, perspective view, showing the control from the carriage of the interlocks and the full-stroke locks for the numeral keys, and the lock for preventing the operation of the rack-shifting mechanism. In this view, the carriage is shown as in a non-computing zone, so that the locking mechanism for the numeral keys is silenced, and the shifting mechanism for the driving rack is locked against possible ac- 95 tuation.

Fig. 4 is a detail section, taken from front to rear, showing the control from the carriage of the computing mechanism as interrupted by the silencing means. 100

Fig. 5 is a detail, vertical section, taken from front to rear, showing the numeral key as operated when the computing mechanism is silenced, illustrating how the numeral key operates idly without operating the actuator 110

and without operating the rack-shifting mechanism.

Fig. 6 is a detail view of the numeral-key-interlock for preventing more than one numeral key being operated at a time. This locking mechanism is shown in its inactive condition, corresponding to being out of the computing zone, or else to a silenced condition of the computing mechanism.

Fig. 7 is a skeleton section, taken from front to rear, showing one of the computing zone-controlling stops as in action, rendering the full-stroke numeral-key-lock effective, the inter-numeral-key-lock effective, and the shifting mechanism for the driving rack effective.

Referring more particularly to the separate parts of the invention, numeral keys 1 and alphabet keys 2 depress key-levers 3, to rock bell-crank 4, so as to swing type-bars 5 up rearwardly against the front side of a platen 6, mounted to rotate in a carriage 7. The carriage 7 is controlled in its step-by-step movements by an escapement mechanism of the usual Underwood type. This includes a rack 8, pivotally mounted on the carriage 7, and normally engaging a pinion 9, connected by a one-way pawl-and-ratchet mechanism, not shown, to the escapement wheel 10. The escapement wheel 10 is controlled in its step-by-step movements by fixed and loose dogs 11 and 12, pivoted to swing back and forth and operated by a universal frame 14 on a rocker 13. The universal frame 14 is operated at the depression of any of the keys 1 and 2 by heels 15, provided on each of the type-bars 5.

In addition to having step-by-step traveling movements, the carriage 7 has tabulating movements to jump from one major column or computing zone to another. This includes tabulating keys 16, which, when depressed, rock key-levers 17 to raise plungers 18, individually, into the path of stops 19, adjustably mounted along a rack 20 carried by the carriage 7. At the operation of any of the tabulating keys 16, the carriage 7 is released from the escapement mechanism by raising the rack 8 out of mesh with the pinion 9. This is done by a lever 21, universal to notches 22, provided on each of the plungers 18. The lever 21, when rocked, draws down on a link 23 to rock a lever 24, carrying at its front end a roller 25 underlying the rack 8. The stops 19 determine various zones or major columns of the typewriter carriage 7. Some of these zones may be solely for the purpose of typewriting, and others may be for the purpose of computing as well as typewriting. In the former case, the stops may be single, as indicated at 26, in Fig. 3; and, in the latter case, for computing, the stops may be double, as indicated at 27, in Fig. 3. In the latter instance the stop 27 is provided with a stretch or reach

28, corresponding to the length of the computing zone, which has a function to be described hereinafter.

The numeral keys 1, in addition to controlling typewriting operations, actuate a computing mechanism to compute the digits as typewritten. For this purpose, each of the numeral keys 1 is provided with a valuating or indexing plate 29, which, in the case of the numeral keys from "1" to "9", are each provided with a cam slot 30, arranged to operate a bail 31, universal to the cam slots. The cam slots 30 are of graded pitch or throw, increasing from a minimum for the "1" key to a maximum for the "9" numeral key, so as to give the bail 31 variably increasing extents of movements, corresponding to the values of the numeral keys operated. This forms an indexing or valuating mechanism which translates the equal movements of the numeral keys into variable driving movements of the bail 31, to correspond with the digital values of the numeral keys actuated.

The bail 31 drives an actuator 32, when connected thereto. The actuator 32, in turn, draws down on a link 33, to thrust forward a driving rack 34. The driving rack 34, as more fully explained in the application, Serial No. 24,390, above-mentioned, is brought into mesh with a gear 35 of a train of gears 36, so as to drive the same an amount corresponding to the value of the numeral key actuated. This train of gears 36 drives a master wheel 37, which, when in any particular computing zone, drives the computing wheels 38 of a totalizer 39, connected to the carriage 7 at a point corresponding to that particular zone. In this way, the values of the numeral keys operated are run into the totalizer 39 step by step as they are typewritten on the work-sheet carried by the platen 6.

The rack 34 is shifted in and out of mesh with the gear 35 from the numeral keys 1, so that they not only drive the rack 34, but control its driving relation with the gear 35 and the train of gears to the master wheel 37. This is done directly in a manner more particularly described in the application, Serial No. 24,390, above-mentioned, but briefly explained at this point. The driving rack 34 is shifted into and out of mesh by a parallel linkage 40, which is connected to be operated by a link 41. The link 41 is operated by a bell-crank 42 when the former is connected for operation by the latter. The bell-crank 42 is connected to be operated by an arm 43 on the rocker 13. It will be remembered that the rocker 13 is operated by the universal frame 14 and the type-bars 5 at the operation of each of the keys 1 and 2.

The connection between the bell-crank 42 and the link 41 is such, however, that the

numeral keys alone can cause the bell-crank 42 to operate the link 41, and thus shift the rack 34. For this purpose, there is pivotally mounted on the link 41 a lever 44, which 5 has an L-shaped slot 45, in which is located a pin 46, secured to the bell-crank 42. The pin 46 and the lever 44 form the means of connection between the bell-crank 42 and the link 41. Normally, the lever 44 is in such 10 relative position to the link 41 that the pin 46 will work idly in the section 47 of the L-shaped slot 45, which extends in parallel, or in the same general direction as the link 41. Thus, when writing with the alphabet keys 15 or with the numeral keys in a non-computing zone, there will be no operation of the link 41 and no shifting of the rack 34.

When a numeral key 1 is operated to effect writing in a computing zone, however, 20 the lever 44 is rocked about its pivot 48, so as to bring the other section 49 of the L-shaped slot 45 into juxtaposition to the pin 46. This forms a rigid connection between the bell-crank 42 and the link 41, so that 25 the driving rack 34 may be shifted relatively to the gear 35, so as to control its driving relation with respect to the same. The shifting of the lever 44 to form a rigid connection between the bell-crank 42 and the 30 link 41 is controlled from the numeral keys 1 themselves. For this purpose, each of the plates 29 is provided with a cam 50, which engages a cross-bar 51 of a bail 52. The bail 52 is connected by a link 53 to an arm 35 54, pivotally mounted at 48 and yieldingly connected to the lever 44 by means of a spring 55. The spring 55 enables the shifting of the lever 44 when its movement is not obstructed, so that whenever it is de- 40 sired to compute and a numeral key is operated, the driving rack 34 may be shifted indirectly by the numeral keys through the universal frame 14 and the rocker 13.

In the present invention, provision is 45 made for locking the lever 44 against a movement tending to come into an effective connecting position when the carriage is not in a computing zone. Under such circumstances, the spring 55 yields idly without a 50 shifting of the lever 44. For this purpose, there is provided on the lever 44 a pin 56 which is engaged by a locking arm 57 when the typewriter carriage 7 is not in a computing zone. This prevents the lever 44 55 from being shifted by the numeral keys 1 to a position to form a rigid connection between the bell-crank 42 and the link 41. Under such circumstances, the bell-crank 42 will vibrate idly when a numeral key is 60 operated without operating the link 41, and thus without shifting the driving rack 34 relatively to the gear 35.

When a computing zone is reached, and it is desired to control the engagement of 65 the driving rack 34 with respect to the

driving train 36, then one of the zone-determining stops 27 having a reach 28, comes into register with a computing zone controller 58 and rocks it rearwardly from the Fig. 1 position to the Fig. 7 position. 70 This controller 58, as a whole, is in the form of a double bell-crank lever pivoted at 59. The pivot 59 is a rock shaft and is rocked each time the controller is rocked by one of the computing zone-controlling stops 75 27. The controller 58 has a lever 60, which is connected by a link 61 to an arm 62 connected to the locking arm 57 by a crank shaft 62^a. The lower arm of lever 60 is limited in its rearward movement by a pin 80 60^a in one of the supporting brackets for shaft 59. In this way, the locking arm 57 is moved from the active position of Fig. 1 to the inactive position of Fig. 7. This permits the lever 44 to rock when a numeral 85 key is operated in a computing zone, thereby enabling the same numeral key, through the escapement mechanism including the universal frame 14, to vibrate the link 41 lengthwise thereof, and thus control the 90 engagement and disengagement of the rack 34 with the gear 35.

Other parts of the computing mechanism are controlled from the computing zone stop 27, so as to bring them into play solely in a 95 computing zone, and thus have the numeral keys relieved of the work of operating them when not in a computing zone. Among the elements controlled in this manner are the interlocks and full-stroke locks for the 100 numeral keys. Pivotally secured to each of the numeral key levers 3, there is provided a pendant 63. Each of these pendants 63 is provided with a crowding interponent 64 pivoted to the pendant 63 and arranged to 105 thrust itself between adjacent pairs of crowding hangers 65 and 66. The hangers 65 and 66 are L-shaped and pivotally mounted so as to form a continuous series of locking arms extending between limiting 110 pins 67 and 68 (Fig. 6). This series of locking arms has a limited lost-motion or back lash, so as to prevent the operation of more than one numeral key at a time when computing. 115

When not computing, it is unnecessary to prevent the overlapping of the operation of two numeral keys at a time, as the operation of two, and sometimes three, type keys can overlap in a rapid operation of the machine; 120 hence, the amount of play or lost-motion in the series of hangers 65 and 66 between the limiting pins 67 and 68 will amount to at least the thickness of two of the crowding interponents 64. This enables two or more 125 numeral keys to overlap in their action when non-computing without a locking action of one numeral key by the other by preventing the intrusion of an interponent 64 in the series of locking hangers 65 and 66. 130

When computing, however, it is desirable that not more than one numeral key shall be operated at a time, as the overlapping of their action might interfere with the accuracy of the computation. To prevent more than one numeral key from operating when in a computing zone, there is provided a special intruding interponent 69, which is arranged to be thrust between a pair of the locking hangers 66 and 65, so as to take up a part of the lost-motion or play in the series of hangers between the limiting pins 67 and 68. This intruding interponent 69 is of sufficient thickness to take up enough of the play so that but one of the interponents 64, carried by the numeral keys, can enter the series of hangers at a time. In this way, when one numeral key is depressed, a second numeral key cannot be depressed, as its interponent 64 will be blocked in its downward movement by the corresponding pair of hangers 65 and 66.

The special crowding interponent 69 is operated from the controller 58, so as to be brought into play when one of the computing zone-controlling stops 27 is in register with the controller 58, corresponding to a computing zone at the printing point of the typewriter. For this purpose, there is secured to the rock-shaft 59, which is operated at this time, a bell-crank 70, one arm of which, 71, is connected by a link 72 to an arm 73 on a rock-shaft 74. The rock-shaft 74 is provided with an arm 75 on which the special crowding interponent 69 is pivotally mounted. The special interponent 69 thus forms a computing zone-controlled interlock for the numeral keys and will only come into play to put this drag on the numeral keys when in a computing zone. The computing zone-controlled lock interponent 69 is guided for its vertical movement by a perforated plate 76, which allows a certain amount of transverse movement, enabling the lock 69 to yield sidewise or lengthwise of the series of hangers 65 and 66, as these hangers must swing to one side or the other a certain amount, according to the location of the particular numeral key actuated which is taking up the space in the series to prevent the simultaneous operation of any other numeral key.

The numeral keys 1 are provided with full-stroke locks to prevent a partial depression or return of a numeral key followed by a subsequent operation of the same numeral key. These full-stroke locks are controlled for the computing zone, so that they need only come into action when computing. Each of the pendants 63 forms part of the full-stroke locking mechanism and is provided with two racks 77 and 78. The rack 77 has upwardly facing teeth so as to prevent the return of the numeral key until completely depressed, and the rack 78 has down-

wardly facing teeth to prevent the depression of the numeral key until completely returned. The rack 77 co-operates with one arm 79 of a double-acting locking dog, and the rack 78 co-operates with the other arm 80 of this double-acting locking dog.

When in a computing zone, the lower arm 79 is within the range of the rack 77, so that upon the depression of a numeral key, the dog 79 will click idly over the teeth of the rack 77, providing the latter is fully depressed. If the numeral key should not be fully depressed, the dog 79, by its engagement with the rack 77, will prevent the return of the numeral key to its uppermost position until it has been fully depressed. After the numeral key has been fully depressed to complete a combined typewriting and computing action, the locking dogs 79, 80, will be swung so as to bring the upper arm 80 into the range of movement of the upper rack 78. This is true for each of the dogs 79, 80, of which there is one for each of the pendants 63. The dogs 79, 80, for this purpose, are mounted on a rock shaft 81, which has a yielding connection by means of a spring 82 to an arm 83. The arm 83 also has a lost-motion pin-and-slot connection 84 with the shaft 81, and is arranged to rock the shaft so as to shift the upper locking arms 80 into reach of the racks 78 after the numeral key in action has completed its down-stroke. The arm 83 is operated from the escapement mechanism, which, in turn, is operated from the numeral key in action at the end of its down-stroke. For this purpose, the arm 83 is connected by a link 85 to a bell-crank 86 (Fig. 1). The bell-crank 86 has a lost-motion connection 87 with the link 85, and is yieldingly connected thereto by means of a spring 88.

A spring 89 tends to operate the bell-crank 86, so as to rock the shaft 81 and bring the upper locking arms 80 into range of the racks 78. This action is opposed, however, by the loose dog 12 of the typewriter escapement mechanism. The bell-crank 86 is connected by a link 90 to a bell-crank 91 pivoted on the rocker 13 and arranged to follow up the loose dog 12 of the escapement mechanism. The loose dog 12 slips off the escapement wheel 10 at the end of the down-stroke of a numeral key when the universal frame 14 is operated, so that the spring 89 is free to operate as the loose dog 12 jumps forwardly to catch the next tooth of the escapement wheel. This will rock the bell-crank 86 so as to draw on the link 85, and thus rock the shaft 81 to bring the locking arms 80 into range of the racks 78. The numeral key, which has been depressed, can then return and will be forced to return completely before it or any other numeral key can be operated.

When not in a computing zone, the dogs

79, 80 are held in an intermediate inactive position in which neither the arm 79 nor the arm 80 is in engagement with the racks 77 and 78, respectively. For this purpose, there 5 is provided on the rock-shaft 81, which carries the dogs 79, 80, a neutralizing bell-crank 92, both arms of which are engaged by an arm 93 provided on the rock-shaft 74. This rock-shaft 74 is connected to be operated by 10 the controller 58, and when not in a computing zone the position of the rock-shaft 74 and the arm 93 will be such that the arm 93 is in engagement with the bell-crank 92 and holds the dogs 79, 80 in their intermediate inactive position. When in a computing 15 zone, one of the zone-controlling stops 27 will shift the controller 58 to such a position as to withdraw the arm 93 from engagement with the bell-crank 92, thereby permitting 20 the rock shaft 81 to assume a normal computing position with the lower arms 79 of the dogs, 79, 80, in engagement with the lower racks 77.

When it is desired to disconnect the 25 numeral keys from the computing mechanism, the actuator 32 may be broken so as to disconnect it from the bail 31. For this purpose, the actuator 32 is formed in two parts pivoted at 94 and connected by a spring 95. 30 The spring 95 normally holds a notch 96 in engagement with a pin 97 on the bail 31. The part 98, provided with the notch 96, may be depressed against the tension of the spring 95 so as to disengage the notch 96 from the 35 pin 97. For this purpose, there is provided a disconnecting shifter 99 pivoted at 100 and operable from a hand-lever 101. The hand-lever 101 has a lost-motion pin-and-slot connection 102 with a link 103 pivotally connected to the shifter 99. In this way the shifter 99 may be operated manually to break the 40 actuator 32, and thus disconnect it from the bail 31. Thus, the bail 31 will be operated idly by the numeral keys 1 without operating 45 the actuator and without rotating the master wheel. The shifter 99 may be operated by other means besides the handle 101. One of these is by means of a link 104 connected to the upper-case shifting mechanism 50 of the typewriter, as is more fully explained in the application of Henry L. Pitman, Serial No. 176,303. It may also be operated from the controller 58, so as to normally disconnect the numeral keys from the actuator 55 when not in a computing zone. For this purpose, the link 72 is provided with a pin-and-slot connection 105 with the shifter 99. This enables the shifter to be operated to its Fig. 1 position, breaking the actuator and 60 disconnecting it from the bail 31 until a computing zone is reached, when the link 72 will be shifted to the position of Fig. 7, relieving the pressure on the part 98, and permitting the spring 95 to reconnect the 65 actuator 32 with the bail 31.

The manual disconnector 101 may be used when it is desired to entirely silence the computing mechanism, irrespective of whether the typewriter carriage 7 is in a computing zone or not. In addition to breaking the 70 actuator 32, so as to interrupt the connection between the numeral keys and the master-wheel drive, the controller 58 may be withdrawn to a position clear of the computing zone-controlling stops 27. For this purpose, 75 the double bell-crank lever 60 of the controller 58 has an arm 106, on which a slide 107 is mounted. This slide 107 has a pin-and-slot connection 108 with the arm 106. Normally, when a combined typewriting and 80 computing operation is desired, a cam head 109 is located in the path of the computing zone controlling stops 27. The slide 107, however, can be depressed so as to remove the cam head 109 therefrom out of the range of 85 the computing zone controlling stops 27.

The slide 107 is connected to be shifted by the manual lever 101. This connection includes an arm 110 pivotally connected to the slide 107 and secured to a rock-shaft 111 90 mounted on the arm 106 at one end, and the bell-crank 70 at the other end. This rock-shaft 111 is provided with a second arm 112 connected by a link 113 to the manually-operated lever 101. This mounting causes the 95 silencing bell crank 110, 111, 112, to rock with the controller 58 and silence the same either in its computing or non-computing determining positions. Thus, the manual lever 101 can simultaneously interrupt the 100 connection between the numeral keys and the master wheel at the actuator 32 and also interrupt the connection between the carriage 7 and the computing mechanism at the controller 58. Under such circumstances, the 105 numeral keys will be relieved of the burden which these parts placed upon them when computing, if it is desired to solely type-write without computing.

The lost-motion connection 102 permits the 110 operation of the shifter 99 without operating the lever 101. The lost-motion connection 105 permits the operation of the shifter 99 without operating the zone-controlling mechanism. The slide 107 is yieldingly held in 115 its active and inactive positions by a detent 114 engaging in notches 115 provided in the slide 107. The controller, as a whole, is held to its work and returned after a zone-controlling stop 27 has passed by means of a 120 spring 116.

It will be seen that, when slide 107 has been moved to the position shown in Fig. 4, spring 116 will hold lever 60 with its lower arm against pin 60^a, and detent 114 will 125 enter upper notch 115 on slide 107, and the combined effect will be to hold handle 101 in disengaging position until the next manual operation of said handle.

It is evident then that a number of ele- 130

ments, which would ordinarily burden the numeral keys, can be shifted out of operation, so as to not drag on the numeral keys when not in a computing zone, and also even 5 when in a computing zone, when it is not desired to compute. These include the inter-key lock, the full-stroke locking mechanism, the shifting of the driving rack into and out of driving engagement with the master-10 wheel train, and the drive to the master-wheel train.

Variations may be resorted to within the scope of the invention, and portions of the improvements may be used without others.

15 Having thus described my invention, I claim:

1. The combination with a typewriter carriage, of computing mechanism, numeral keys for controlling the action of the typewriter carriage and said computing mechanism, full-stroke mechanism for said numeral keys, and means for controlling the activity of said full-stroke mechanism, according to the position of said carriage in 25 determining different zones of typewriting and computing.

2. The combination with a typewriter carriage, of computing mechanism, numeral keys for controlling both said typewriter carriage and said computing mechanism, full-stroke mechanism for said numeral keys, and silencing means for said full-stroke mechanism operated from said typewriter carriage.

3. The combination with a typewriter carriage, of computing mechanism, numeral keys for operating both said typewriter carriage and said computing mechanism, a double-acting full-stroke mechanism for insuring the complete up-and-down strokes of said numeral keys, a stop carried by said carriage, and means for shifting said full-stroke mechanism to an active position controlled by said stop.

4. The combination with a typewriter carriage, of computing mechanism, numeral keys for controlling both said typewriter carriage and said computing mechanism, full-stroke mechanism for said numeral keys including pendants having oppositely-facing pairs of racks for each numeral key, double-armed dogs for said pendants, means tending to hold one arm of each of said dogs in the range of one rack of each pair, means 55 opposing this tendency, and a stop carried by said carriage connected to overcome said last-mentioned means.

5. The combination with a carriage, of computing mechanism, numeral keys for controlling both said carriage and said computing mechanism, an escapement mechanism controlled by said numeral keys for controlling the position of said carriage, full-stroke mechanism for said numeral keys 65 controlled by said escapement mechanism,

and means for controlling said full-stroke mechanism from said carriage, so as to operate solely when said computing mechanism is being actuated.

6. The combination with a typewriting mechanism, of computing mechanism, numeral keys controlling both said typewriting and computing mechanisms, interlocking mechanism for said numeral keys preventing the same numeral key and any other numeral key from being operated before the numeral key just operated, to control said computing mechanism, has completed its action, and controlling means for insuring the operation of said interlocking mechanism solely when computing.

7. The combination with a typewriter carriage, of computing mechanism, numeral keys for controlling the action of both said typewriter carriage and said computing mechanism, a normally-inactive interlock for said numeral keys, and a computing zone-controlling stop carried by said carriage connected to bring said interlock into play.

8. The combination with a typewriter carriage, of computing mechanism, numeral keys for controlling the action of said typewriter carriage and said computing mechanism, a series of pendants, one for each of said numeral keys, a crowding lock operated by said pendants having a lost-motion permitting the intrusion of at least two of said pendants, and an auxiliary interponent operated from said carriage to decrease the 100 lost-motion in said crowding lock to the capacity of one pendant, so as to prevent the operation of more than one numeral key at a time.

9. The combination with a typewriter carriage, of computing mechanism, numeral keys for controlling the action of said typewriter carriage and said computing mechanism, a series of pendants, one for each numeral key, a crowding lock operated by said pendants having a lost-motion permitting the intrusion of at least two of said pendants, an auxiliary crowding interponent for taking up the lost-motion in said crowding lock to reduce the same to the capacity of 110 but one pendant, so as to permit but one numeral key to be operated at a time, a computing zone-controlling stop carried by said carriage, and connections operated by said stop when said carriage is in a computing 115 zone to intrude said interponent in said crowding lock, so as to prohibit the operation of more than one numeral key when computing.

10. The combination with a typewriter carriage, of computing mechanism, numeral keys for controlling the action of said typewriter carriage and said computing mechanism, a normally silent lock, preventing, when active, the operation of more than one 120

numeral key at a time, a computing zone-controlling stop carried by said carriage, connections operated by said stop when said carriage is in a computing zone, for rendering said numeral key lock effective, so that more than one numeral key cannot be operated at a time when computing, and means for silencing said connections from said computing zone-controlling stop to said lock, whereby said lock may be passive when said carriage is in a computing zone.

11. The combination with a typewriter carriage, of computing mechanism, numeral keys for controlling the action of said typewriter carriage and said computing mechanism, a series of pendent interponents, one for each of said numeral keys, a crowding lock having a lost-motion corresponding to a capacity of at least two of said interponents on said numeral keys, an auxiliary crowding interponent for taking up a portion of the lost-motion in said crowding lock, so as to prevent the intrusion of more than one interponent at a time, and thus prevent the operation of more than one numeral key at a time, a computing zone-controlling stop carried by said carriage, a controller operated by said stop when said carriage is in a computing zone, connected to operate said auxiliary interponent, so as to render said crowding lock effective, and means for silencing said controller, so as to prevent the bringing into play of said lock by said zone-controlling stop.

35 12. The combination with a typewriter carriage, of means, including numeral keys, for controlling the action of said carriage, a totalizer, a numeral key-operated driving mechanism for said totalizer, having a point of interruption, enabling effective action solely on one stroke of the numeral key, numeral-key-operated means for making and breaking said driving mechanism at said point of interruption, a lock for preventing the operation of said last-mentioned means, and carriage actuated means for releasing said lock.

13. The combination with a typewriter carriage, of means, including numeral keys, for controlling the action of said carriage, a totalizer, a driving mechanism for said totalizer operated by said numeral keys, and including a point of interruption, so as to drive said totalizer solely on one stroke of the numeral key actuated, numeral-key-actuated means for making and breaking said driving mechanism at said point of interruption, computing zone-controlling means carried by said carriage, and means for controlling the operation of said make-and-break means from said computing zone-controlling means.

14. The combination with a typewriter carriage, of a totalizer, means, including numeral keys, for controlling the action of said

typewriter carriage, driving connections between said numeral keys and said totalizer, including a point of interruption, a make and break mechanism for said point of interruption operated by said numeral keys, a control for the operation of said make and break mechanism, governed from said carriage, and silencing means for said control.

15. The combination with a typewriter carriage, of means, including numeral keys, for controlling the action of said carriage, a totalizer, driving connections for said totalizer operated by said numeral keys, said driving connections having a point of interruption, enabling the drive of said totalizer solely on one stroke of said numeral keys, a make and break mechanism for said point of interruption, silencing means for said make and break mechanism, a computing zone-controlling stop carried by said carriage, and connections for operating said silencing means from said computing zone-controlling stop.

16. The combination with a typewriter carriage, of an escapement mechanism for said typewriter carriage, means, including numeral keys, for controlling the action of said escapement mechanism, a totalizer, a driving train from said numeral keys to said totalizer having a point of interruption, a make-and-break connection for said point of interruption, means for operating said make-and-break connection from said escapement mechanism, connections enabling said numeral keys to control the operation of said make-and-break connection by said escapement mechanism, and a lock for preventing the operation of said last-mentioned connections.

17. The combination with a typewriter carriage, of an escapement mechanism for said typewriter carriage, means, including numeral keys, for controlling the action of said escapement mechanism, a totalizer, a driving train from said numeral keys to said totalizer having a point of interruption, a make-and-break connection for said point of interruption, means for operating said make-and-break connection from said escapement mechanism, connections enabling said numeral keys to control the operation of said make-and-break connection by said escapement mechanism, a lock for preventing the operation of said last-mentioned connections, and computing zone-controlling means governed from said carriage for releasing said lock when in a computing zone.

18. The combination with a typewriter carriage, of an escapement mechanism for said typewriter carriage, means including numeral keys, for controlling the action of said escapement mechanism, a totalizer, a driving train from said numeral keys to said totalizer having a point of interruption, a make-and-break connection for said point of interruption, a

of interruption, means for operating said make-and-break connection from said escapement mechanism, connections enabling said numeral keys to control the operation 5 of said make-and-break connection by said escapement mechanism, a lock for preventing the operation of said last-mentioned connections, computing zone-controlling means governed from said carriage for releasing 10 said lock when in a computing zone, and manually-operated controlling mechanism for silencing the control of said lock from said carriage.

19. The combination with a typewriter carriage, of numeral keys for controlling the action of said carriage, a totalizer, a driving train from said numeral keys to said totalizer, including an actuator, means for breaking 15 said actuator, so as to interrupt the connection between said numeral keys and said totalizer, a shifter for breaking said actuator, computing zone-controlling means carried by said carriage, and means for operating 20 said shifter from said computing zone-controlling means.

20. The combination with a typewriter carriage, of numeral keys for controlling the action of said typewriter carriage, a totalizer, a driving train between said numeral keys and said totalizer, a shifter for interrupting 25 said driving train, computing zone-controlling means carried by said carriage, connected to operate said shifter, manual means for operating said shifter to control the activity of the driving train between 30 said numeral keys and said totalizer, and connections from said manual controlling means for governing the effectiveness of said zone-controlling means.

40 21. The combination with a typewriter carriage, of numeral keys for controlling the action of said typewriter carriage, a totalizer, a driving train from said numeral keys to said totalizer, including an actuator, a shifter for disconnecting 45 said actuator, a computing zone-controlling stop carried by said carriage, a controller operated by said stop, and a link operated by said controller connected to operate said shifter.

50 22. The combination with a typewriter carriage, of numeral keys for controlling the action of said typewriter carriage, a totalizer, a driving train from said numeral keys to said totalizer, including an actuator, a shifter for disconnecting 55 said actuator, a computing zone-controlling stop carried by said carriage, a controller operated by said stop, a link operated by said controller connected to operate said shifter, said controller comprising a bell-crank and a slide, and means for shifting 60 said slide into and out of range of said stop carried by said carriage, so as to determine the activity and inactivity of the control of the driving train

between said numeral keys and said totalizer 65 from said carriage.

23. The combination with a typewriter carriage, of means, including numeral keys, for controlling the action of said carriage, a totalizer, a driving train between said totalizer and said numeral keys, having a point of interruption, make-and-break connections for said point of interruption controlled by said numeral keys, locking means for said numeral keys, and a carriage-operated means 75 for bringing said connections and said locking means into play solely when in a computing zone.

24. The combination with a typewriter carriage, of means, including numeral keys, for controlling the action of said typewriter carriage, a totalizer, a driving train between said totalizer and said numeral keys, having a point of interruption, enabling the drive of said totalizer from said numeral keys 80 solely during one stroke of said numeral keys, said driving train also having a second point of interruption for silencing the drive from said numeral keys to said totalizer, a make-and-break connection for said first-mentioned point of interruption controlled from said numeral keys, and computing zone-determining means operated 85 from said carriage for controlling the connection at said second-mentioned point of interruption and the operation of said make-and-break connection.

25. The combination with a totalizer, of numeral keys, a driving train between said numeral keys and said totalizer, including a point of interruption, a link connected to said driving train to make and break the same at the point of interruption, operating means for said link including a bell-crank and a lever having a fast and loose connection to said bell-crank, said lever being pivotally mounted on said link, and shiftable from a position where said bell-crank has an idle movement relative to said lever, and thus relative to said link, to a position where 100 said bell-crank has a rigid connection to said lever, and thus to said link, a lock for preventing the shifting of said lever, an arm for shifting said lever, a spring forming a yielding connection between said arm and said lever, enabling the shifting of said lever by said arm when said lock is moved to an inactive position, and connections enabling the operation of said arm by said numeral keys, so as to control the make and break of 105 said driving train between said numeral keys and said totalizer when said lock is inactive.

26. The combination with a totalizer, of numeral keys, a driving train between said numeral keys and said totalizer, including a point of interruption, a link connected to said driving train to make and break the 110

- same at the point of interruption, operating means for said link including a bell-crank and a lever having a fast and loose connection to said bell-crank, said lever being pivotally mounted on said link, and shiftable from a position where said bell-crank has an idle movement relative to said lever, and thus relative to said link, to a position where said bell-crank has a rigid connection to said lever, and thus to said link, a lock for preventing the shifting of said lever, an arm for shifting said lever, a spring forming a yielding connection between said arm and said lever, enabling the shifting of said lever by said arm when said lock is moved to an inactive position, connections enabling the operation of said arm by said numeral keys, so as to control the make and break of said driving train between said numeral keys and said totalizer when said lock is inactive, means for operating said bell-crank from said numeral keys, and computing zone-controlling means carried by said carriage, connected to operate said lock, so as to place the drag of said make and break of said driving train on said numeral keys solely when in a computing zone.
27. The combination with a typewriter carriage, of means, including numeral keys, for controlling the action of said typewriter carriage, a totalizer, a driving train between said numeral keys and said totalizer, full-stroke locks for said numeral keys, interlocks for said numeral keys, silencing means for said driving train, and means controlled from said carriage for automatically relieving said numeral keys of the burden of operating said driving train, said interlocks and said full-stroke locks when said carriage is in non-computing zones.
28. The combination with a typewriter carriage, of means, including numeral keys, for controlling the action of said carriage, a totalizer, a driving train between said numeral keys and said totalizer having a point of interruption and a point of disconnection, numeral-key-operated means for making and breaking said driving train at said point of interruption during an operation of said numeral keys, means for disconnecting said driving train at said point of disconnection, and carriage-controlled means for silencing said make-and-break means and bringing into play said disconnecting means when said carriage is in non-computing zones.
29. The combination with a carriage, of numeral keys, numeral-key-controlled computing mechanism, numeral-key-controlled escapement mechanism for said carriage, full-stroke mechanism for said numeral keys, connections whereby said full-stroke mechanism is rendered effective in one direction or the other by said escapement mechanism, and carriage-controlled means for rendering said full-stroke mechanism ineffective.
30. The combination with a typewriter carriage, of computing mechanism, means, including numeral keys, for controlling the action of said typewriter carriage and of said computing mechanism, a lock for preventing the operation of more than one numeral key at a time, carriage-controlled means to render said lock effective or ineffective, and means to render said carriage-controlled means ineffective.
31. The combination with a carriage, of numeral keys, numeral-key-controlled computing mechanism, numeral-key-controlled escapement mechanism for said carriage, mechanism to insure a full down stroke of said numeral keys, and means controlled by the escapement mechanism to render said full-stroke mechanism ineffective at the end of the down stroke of a depressed key, so as to permit the key to rise.
